UNITED STATES PATENT OFFICE.

LEMAN P. RIDER, OF PITTSBURG, PENNSYLVANIA.

PROCESS OF AND FURNACE FOR BURNING WET VEGETABLE, ANIMAL, OR MINERAL MATTER.

SPECIFICATION forming part of Letters Patent No. 352,662, dated November 16, 1886.

Application filed March 24, 1886. Serial No. 196,434. (No model.)

To all whom it may concern:

Be it known that I, LEMAN P. RIDER, a citizen of the United States, residing at Pittsburgh, in the county of Allegheny and State 5 of Pennsylvania, have invented certain new and useful Improvements in Processes of and Furnaces for Burning Wet Vegetable, Animal, or Mineral Matter; and I do hereby declare the following to be a full, clear, and exact description of the invention, such as will enable others skilled in the art to which it appertains to make and use the same.

The invention relates to the process of and a furnace for burning wet or green vegetable, 15 animal, or mineral matter for generating steam, and for other heating purposes.

The invention will be hereinafter described, and particularly pointed out in the claims.

In the accompanying drawings, which form 20 a part of this specification, Figure 1 represents a vertical longitudinal section; Fig. 2, a side elevation; Fig. 3, a cross-section on line *xx*, Fig. 1; and Fig. 4, an enlarged perspective view of one of the side doors of the furnace.

In practicing my invention the matter to be burned, whether vegetable, animal, or mineral, is deposited in the furnace in coniform 30 heaps or piles, with their bases resting upon suitable grate-bars. Preference is given to the shaking-bars shown and described in Letters Patent of the United States granted to me January 23, 1877, No. 186,436; July 17, 1877, Nos. 193,180 and 193,181; but any efficient and practical bars will answer the purpose. The fuel is fed alternately through suitable openings arranged in parallel rows in the crown of the furnace; a pile having been deposited on one side of the furnace, the 40 next is fed through an opening diagonally opposite to the one through which the first was fed, and this operation is continued until all of the charges are deposited.

Reference being had to the drawings and 45 the letters marked thereon, A represents the furnace, which is provided with a movable or shaking grate, B, the end bars, *a b*, of which are removable by being withdrawn from the forward and rear ends of the furnace. The 50 said bars rest in slots or bearings *c d*, supported by the masonry. The crown of the furnace is arched, and constructed of brick

laid with their ends exposed to the products of combustion, as shown in cross-section in Fig. 3.

Above the furnace is a series of hoppers, C, arranged in parallel rows, which communicate with the furnace and are provided with covers *e* and valves *f*, through which fuel is supplied.

D represents a bell-mouthed opening in the front wall of the furnace, and *g* a branch or nozzle leading from a pipe, E, for supplying gas, when it is convenient for use, to heat the walls of the furnace preparatory to supplying the wet or green fuel. When gas is not available, ordinary fuel—such as wood or coal—is used for heating the furnace.

On each side of the furnace are arranged doors F, which are on the same or nearly the same vertical plane with the hoppers C, and afford access to the interior of the furnace through the openings G, to remove any unconsumed matter that will not pass through the grate-bars. The cleaning of the furnace is also expedited by the removal or withdrawal of the end bars, *a b*, by which much of the ashes and other matter can be drawn off into the ash-pit.

The doors F consist of a frame, *h*, of wrought or cast metal, which is filled with fire-brick and crossed by a bar, *i*, to which is pivoted, at *j*, an arm, *k*, and the upper end of said arm is clamped to a projecting stud, *l*, by a nut, *m*. The arm *k* is provided with a slot, *n*, by which it adjusts itself to the closed or open position of the door.

H is a casting, upon the lower front side of which is formed a horizontal flange, *o*, upon which the door rests, and from said flange and at right angles thereto projects a flange, *p*, to prevent the door from being displaced laterally. To prevent the admission of air to the furnace through the side openings, G, the doors F, when closed, are sealed with clay. The upper surface of the flange *p* is corrugated, as shown, and each corrugation forms a seat or support for the iron bar used to stoke the fire. The castings H are secured to and held in position against the masonry by clamping-plates I, which in turn are secured to the masonry by bolts or tie-rods in the usual manner.

In the rear of the ash-pit is a vault, J, through which access is had to withdraw the short bars *a* of the grate.

K is a combustion-chamber, the crown of

which is arched and in the same horizontal plane as that of the furnace A; but the bottom of the chamber is raised considerably above the bottom of the furnace, and the area of the 5 combustion-chamber in cross-section is equal to about one-third ($\frac{1}{3}$) of that of the furnace. By this construction the products of combustion are retarded in their passage through the combustion-chamber and a thorough mingling 10 of the gases effected.

Immediately in the rear of the combustion-chamber is a working-chamber, L, which may be utilized to consume fuel, garbage, or other waste material; or it may be used as a metal-lurgical furnace. The side walls of this chamber are provided with openings G' and doors H', of the same construction as those applied to the furnace, and the bottom of the chamber is constructed of masonry. Hoppers C' are 15 also provided for supplying fuel to said chamber.

In the rear of the chamber L, and forming an outlet therefrom, is a throat or flue, M, which communicates with the stack N; or by closing 25 the damper O, which is operated by a lever, q, and opening the sliding gate or damper P, the products of combustion may be conducted through a flue, Q, to a steam-boiler, R, and be passed through the flues thereof to generate 30 steam.

The draft of the furnace is controlled by the damper O and the steam-jet from the pipe r, which terminates in the stack N, and is provided with a regulating-valve, s. P' is a vault 35 or chamber to receive ashes or the sweepings from the boiler fire tubes or flues, and is provided with a suitable door (not shown) for ingress and egress.

The operation is substantially as follows: 40 The furnace A is heated by gas or other fuel, and when sufficiently hot the wet or green vegetable, animal, or mineral fuel is charged into the hopper C, the covers e replaced, and the valve f of one of the hoppers withdrawn, 45 when the contents of the hopper will be discharged into the furnace and assume the form of a cone, with its base resting upon the grate-bars. A hopper diagonally opposite the one first discharged is now opened and its charge 50 deposited in like manner, the fuel thus being deposited out of the line of the draft of the preceding charge. This operation is repeated until all of the hoppers have been discharged into the furnace, when they are refilled and 55 the same operation continued. The several charges from the hoppers falling upon the grate-bars or the bottom of the furnace and assuming the forms of cones or pyramids, their bases will extend out into contact with each 60 other, and in this form the vapors and gases of the wet or green fuel are rapidly driven off. The air supplied to the furnace is admitted only through the grate and against the bases of the coniform piles of fuel, entering the body 65 thereof, passing upward through the masses, and entirely enveloping the outer surfaces of

the several piles. By this operation the gases of the fuel are gradually evolved and liberated and the outer surfaces of the cones subjected to intense heat, which is reflected back upon 70 the several burning piles by the reverberatory action of the crown of the furnace, and the result is a rapid distillation of gases, which are driven through the combustion-chamber K in the form of a white flame and the gases 75 thoroughly intermingled by their passage through said combustion-chamber. The products of combustion are then utilized in the working-chamber L for consuming garbage or other fuel, or for other heating purposes. 80 From the chamber L the products of combustion are conducted to a steam-boiler, R; or they may be permitted to escape through the stack N. When the products from the furnace A are utilized for consuming garbage or other 85 waste matter in the chamber L, the combustion of said matter is effected entirely by surface action, as no air is admitted to said chamber, and the result is a perfect incineration of the matter charged into said chamber. 90

In the operation of burning wet fuel—such as garbage, bagasse, or tan-bark—the steam arising therefrom is decomposed, mingled with the gases, and burned, thus utilizing all the available combustible matter contained in the 95 fuel.

In another application, renewed March 6, 1886, No. 194, 358, I have claimed the process of burning fuel in the furnace shown, and also some of the features of its construction, and do not, therefore, herein claim such matter.

Having thus fully described my invention, what I claim is—

1. The process of burning wet or green fuel, garbage, &c., which consists in depositing said 105 matter in coniform piles in a close chamber from which atmospheric air is excluded, and to which the products of combustion from a furnace are admitted, and surrounding the exposed surfaces of the fuel with said products 110 of combustion, substantially as described.

2. The combination of a furnace, a close working-chamber from which atmospheric air is excluded, and provided with a series of parallel charging-openings through its crown, and 115 a combustion-chamber between the furnace and the working-chamber, which forms the only channel through which gases are admitted to the working-chamber, substantially as described. 120

3. The combination of a furnace, a close working-chamber from which atmospheric air is excluded, and provided with a series of parallel charging-openings through the crown, and side openings having doors for sealing 125 the same, and a combustion-chamber intermediate of the furnace and the working-chamber, which forms the only channel through which gases are admitted to the working-chamber, substantially as described. 130

4. The combination of a furnace, a working-chamber, and a combustion-chamber interme-

diate of the two, and the crowns of all of said parts arranged on the same plane, substantially as described.

5. The combination of a furnace, a combustion-chamber, a working-chamber, a flue or passage leading therefrom, a gate or valve controlling said flue, and a steam-generator, substantially as described.

6. A furnace-door consisting of an open metallic frame filled with fire-brick, and a bar crossing the frame, in combination with an arm and a clamping device, substantially as described.

7. In a furnace, a plate provided with a plane horizontal flange and a corrugated vertical flange, in combination with a sliding door, substantially as described. 15

In testimony whereof I affix my signature in presence of two witnesses.

LEMAN P. RIDER.
